UNITED STATES PATENT OFFICE.

GEORGE K. COGSWELL, OF DARLOW, KANSAS.

ACETYLENE-GAS GENERATOR.

1,262,177.

Specification of Letters Patent. Patented Apr. 9, 1918.

Application filed April 8, 1915. Serial No. 20,046.

To all whom it may concern:

Be it known that I, GEORGE K. COGSWELL, a citizen of the United States, residing at Darlow, in the county of Reno and State of Kansas, have invented certain new and useful Improvements in Acetylene-Gas Generators, of which the following is a specification.

This invention relates to an improved acetylene gas generator and the principal object of the invention is to provide a generator of such construction as to permit gas to be generated in a selected generating tank while the second tank is being discharged for cleaning and to also provide an improved purifying mechanism for the gas prior to the gas entering the service pipe.

Another object of the invention is to provide an improved type of generating tank and to also provide within the generating tank an improved type of carbide holding receptacle.

Another object of the invention is to provide a device of this character which effectually excludes the entrance of air into the distributing pipes when it is being recharged.

Another object of the invention is to minimize the waste of gas when the device is being recharged.

Another object of the invention is to provide an acetylene gas generator of the class described which will be very compact and thus take up a small amount of room and at the same time be very strong, the various parts being securely held in place and thus preventing it from having any movement which would cause the various joints to work loose.

This invention is illustrated in the accompanying drawings, wherein:—

Figure 1 is a view of the generator showing one of the tanks in elevation and the second tank in vertical section.

Fig. 2 is a view of the generator showing one of the tanks and the purifying chambers in top plan and the second generating tank in section along the line 2—2 of Fig. 1.

The generating tanks 10 and 11 are positioned within the base frame 12 and are con-

nected by the conduit pipes 13 so that water may pass from one tank into the other thus permitting both tanks to be filled by pouring water into one of the tanks through the spout 14 shown upon tank 10. If desired 55 each of these tanks may be provided with a spout 14 thus permitting the tanks to be rapidly filled by pouring water through both of the spouts simultaneously.

Each of the tanks is provided with a bell 60 15 which is slidably mounted within the respective tank and has its lower end portion reinforced by the band 16 which band is formed of channel iron as clearly shown in Fig. 1. The conical top or head 17 of each 65 bell 15 is provided with a collar or flange 18 at its junction with the body portion of the bell, this flange engaging the upper edge of the tank and reinforcing band 19 which latter is positioned about the upper edge 70 thereof above the spout 14 and coöperates with the flange 18 so as to limit the downward movement of the bell within the tank and suspend the same therein. Brackets 20 are positioned within the tank and engage 75 the lower end of the bell to support the same and prevent the entire weight of the bell from being placed upon the flange or collar 18. Danger of the collar being bent or broken from overstrain is therefore eliminated.

The head 17 of the bell 15 is formed with a central opening which is closed by a cover 21 which is provided with a flange which rests upon the upper edge portion or neck 85 22 of the head 17 except when it is normally raised from said neck. The cover 21 comprises a cylindrical portion or flange 23 which is closed at its upper end and open at its lower end, as clearly illustrated in 90 Fig. 1. A double-walled water jacket 24, having a closed lower end and an open upper end, has its outer wall secured to the neck 22 by a fluid-tight joint, while its inner wall is spaced apart from the outer wall 95 sufficiently to allow free movement of the cylindrical portion 23 of the cover 21, and also provides a space at each side of the element 23 for containing a water seal for preventing the passage of gas from the bell to 100

- the open air. The inner wall of the water jacket surrounds a central space through which a carbide holder may be passed into and removed from the water in the tank 11.
- 5 A U-shaped bracket 27 is secured to the cover member of the bell 21 by the rivets which hold the handle 26 in place and has its arms 28 provided with hooks 29 at their free ends to engage the perforated carbide receptacle 30 and suspend the same in the position shown in Fig. 1 so that the carbide will be submerged in the water with which the generating tank is filled. It should be noted that the walls of the bell 15 are positioned in spaced relation to the walls of the generating tanks and therefore a water seal will be provided preventing the carbids from leaking out of the bell when the generator is in operation.
- 10 The purifying tanks 31 and 32 are placed within the frame 12 between the generating tanks 10 and 11 and upon opposite sides of the frame and are connected with the outlet pipes 33 and 34 leading from a point within 15 the bell above the water line to a point adjacent the bottom of the tank and out through the same and communicating with the lower end portions of its purifying tank. Referring to Fig. 1, it will be noted that the outlet pipe 33 has its upper end opening into an annular chamber between the water jacket 24 and the inner wall of the bell 15, and that said water jacket extends below the normal level of water in the tank 15, while 20 the pipe 33 opens a considerable distance above the water level. Therefore, when the bell 21 is removed for recharging the apparatus, the annular space into which the pipe 33 opens remains hermetically sealed, thereby preventing escape of gas from the bell 15, and at the same time preventing the entrance of air into the bell 15 or into the pipe 33. The purifying tanks may be filled with any suitable filtering material such as 25 mineral wool or any material which will cleanse the gas and remove moisture from the same so that when the gas passes out through the service pipes 35 and 36 it will be clean and dry and thus burn well. These 30 pipes can be directed to the gas mains supplying the house and can be provided with separate control valves so that gas may be fed from one tank at a time while the other is being recharged or cleaned or they may 35 be led to a suitable storage tank where the gas can be stored until needed for use. A small pet cock 37 is placed in the pipe 33 so that the pipe can be drained of any water or other fluid which may collect in the same 40 and a drain pipe 38 leads from the pipe 34 to a point adjacent the tank 31 where it is also provided with a pet cock 39 permitting the fluid collecting in the pipe 38 to be 45 drained out.

When this device is in use carbids may be 65 placed within one of the receptacles 30 after the tanks have been filled with water and after the receptacle 30 has been placed between the resilient arms 28 of the U-shaped supporting bracket 27 the cover is put in place as shown in Fig. 1 with the carbide receptacle submerged. The carbide will then be dissolved by the water until sufficient gas has been generated to raise the bell and move the receptacle 30 out of the water. 75 The bell will provide sufficient pressure to force the gas through the outlet pipe and into the purifying tank through which it will pass and then through the service pipes to the house. As the gas is used the bell 80 will gradually descend until the carbide receptacle is again immersed and more gas will be generated until the bell is again raised a sufficient distance to raise the carbide receptacle out of the water. After all of the 85 carbid in the receptacle has been used the second tank can be charged and the gas generated in the second tank can be conveyed to the building through its service pipe while the first tank is being recharged. It 90 is of course better to charge the second tank before the gas in the first tank is completely used so that there will be no time when the supply of gas will be exhausted. Of course 95 if desired for any reason to have an unusually large quantity of gas supplied at one time both tanks can be simultaneously operated and double the normal quantity of gas provided. When desired to clean the tanks the cover is removed and the carbid 100 receptacles can then be emptied without it being necessary to remove the bell. Water collecting in the outlet pipes 33 and 34 can be drawn off through the pet cocks 37 and 39 and when necessary the water can be 105 removed from the generating tanks 10 and 11. It will thus be seen that an acetylene gas generator has been provided which is very simple in construction but which is very efficient in operation and which is so 110 constructed as to be very convenient. The tanks of course can be made any size desired and of any suitable material. This tank will be very light and can therefore be easily handled without causing undue strain on 115 the part of the operator.

What is claimed is:—

An acetylene gas generator comprising a generating tank adapted to contain water at a normal level, a bell mounted for vertical movement in said tank and having an opening through its top, a double-walled water jacket having a closed bottom and an open top and a central space surrounded by its inner wall, said jacket being fitted within the opening of said bell and carried by the latter, a cover provided with a depending flange adapted to be positioned between the

walls of said double-walled jacket, the central space of said water jacket being in open communication with the interior of said bell, a carbide holder carried by said cover and located within said space, and an outlet pipe communicating with a space above said normal water level and between the inner wall of the first said bell and the outer wall of said water jacket when the latter extends below said normal water level. 10
In testimony whereof I affix my signature in presence of two witnesses.

GEO. K. COGSWELL.
